CORD CARRIER FOR BRAIDING MACHINES

Roger M. Scott and John G. Aldrich, Providence,
R. I., assignors to New England Butt Company,
Providence, R. I., a corporation of Rhode
Island

Application April 10, 1936, Serial No. 73,672

5 Claims. (Cl. 96—15)

The present invention relates to cord carriers for braiding machines and more particularly to the type of carrier adapted for use with the braiding of relatively heavy cord, as in the formation of cordage, heavy braids or the like.

One object of the invention is the provision of a simple and efficient device of this character adapted particularly for use with heavy cords and having the parts so constructed and arranged as to provide relatively smooth and uniform operation in the normal use of the mechanism.

Another object of the invention is the provision of simple and efficient guiding means for the tension member so arranged as to provide relatively smooth and accurate guides which are positively held against displacement, while at the same time being capable of ready removal or replacement.

A further object of the invention is the provision of a combination of elements adapted for applying tension to the cord strand in such a manner as to efficiently tension the same without rendering it liable to abrasion or injury through being caught in the moving parts of the tensioning mechanism.

Other objects and advantages of the invention relate to various improved details of construction and combinations and arrangements of the parts as will be more fully set forth in the detailed description to follow.

Referring to the drawing:

Fig. 1 is an elevational view of the carrier member, showing a cord carrying bobbin in position thereon and illustrating generally the path of travel of the cord strand from the bobbin to the thread delivery eye.

Fig. 2 is an elevational view of the carrier with the bobbin removed, showing the position of the tension member in normal operation for applying tension to the cord, as well as an equalizing member shown in operative relation with the spindle for assisting in maintaining substantial uniformity in the rate of travel of the cord.

Fig. 3 is a vertical sectional view through one of the tension member guide shafts, showing the position of the parts and illustrating their ready accessibility, and,

Fig. 4 is a horizontal sectional view, taken substantially along the line 4—4 of Fig. 2.

In the embodiment of the invention illustrated herewith 1 designates the base of the carrier which is adapted to seat upon the top plate of the braiding machine for travel thereon in a predetermined path under the influence of any suit-

able form of driving mechanism (not shown), the oscillatory movement of the carrier being controlled by guide means 2 and 4 which may be formed integral with the base after a manner well known in the art. The base 1 is preferably formed as a single casting and carries a spindle 3 for supporting a reel or spool 5 having its axis of rotation vertically positioned relative to the horizontal plane of the top plate of the braider. The spool 5 is provided with the usual ends 6 and 7, the end 7 having a plurality of teeth 8 projecting from the outer face thereof for a purpose which will be more fully described.

A frame member 10 may be formed integral with or carried by the base 1 from which it extends upwardly in substantial parallelism with the spindle 3. The frame 10 is provided with oppositely positioned transverse arms 12 extending outwardly from opposite sides thereof for supporting with the base a pair of spaced guide members 14 and 15 in parallel relation with each other for guiding a movable tension member 16.

Each transverse arm 12 is provided with an opening 17 located in opposed relation with a threaded opening 18 formed in the base 1 for the reception of one of the spaced guide members. Each guide member comprises an enlarged portion 20 and a reduced portion 21 the end of which is adapted to be threaded within the opening 18 formed in the base plate. The enlarged portion 20 forms with the reduced portion 21 an external shoulder 22 which is engageable with one end of a coiled spring 23 positioned within a sleeve 24 carried by or forming a part of the tension member 16. The opposite end of the coiled spring 23 seats against an internal shoulder 25 carried by the sleeve 24 whereby the tension of the springs 23 is effective to urge the tension member 16 towards the base 1.

The frame member 10 is provided with a guide opening 26 which may be located at a suitable point intermediate the base 1 and the oppositely positioned transverse arms 12 for directing the cord 27 outwardly from the spool 5 towards that portion of the tension member connecting the sleeves 24. A thread groove 28 may be formed in that face of the frame member 10 which is located outwardly from the spool 5 and extends downwardly of the frame member from the guide opening 26 towards a cord guide member 29 carried by the tension member 16 and located substantially midway between the sleeves 24.

The frame member 10 extends above the transverse arms 12 and is provided with a cord delivery eye 30 to which the cord 27 passes from the

cord guide member 29 for delivery to the formed material. A shallow groove 32 may be formed in the outer face of the frame member 10 adjacent to the delivery eye 30 to prevent excessive wearing 5 contact of the cord with the surface of the frame member in its travel to the delivery eye.

An outwardly projecting arm 34, carried by the frame member 10 above the arms 12, is located in opposed relation with one of the arms 12; and 10 these opposed arms are provided with aligned openings to slidably receive a shaft 36 provided at one end thereof with a detent 37 angularly positioned to engage one of the teeth 8 carried by the end 7 of the spool 5.

15 The detent 37 is so positioned as to slidably engage one face of an angular lug 38 carried by the frame member 10 when in tooth engaging position, which lug serves as a supporting bearing for the detent 37 and prevents it from being 20 turned out of engagement with a tooth 8 through the pressure exerted by tension applied to the cord. The lower end portion of the shaft 36 extends downwardly below the arm 12 and is engageable by a lug 40 carried by the tension member 16 when the tension member is raised to a 25 point at or approaching its position of greatest tension. A coiled spring 42 is carried by the shaft 36 between the arms 34 and 12, and may have one end thereof bearing against the arm 34, as 30 indicated at 43, while the opposite end may be secured to the shaft 36, as by means of a pin 44. This manner of connecting the spring to the shaft 36 and lug 34 automatically rotates the shaft 36 into position to bring the detent 37 into tooth 35 engaging position after the shaft 36 has been turned to permit the removal and replacement of a bobbin, while the compression of the spring 42 caused by upward movement of the shaft 36 serves to return the shaft into position for the detent 37 40 to engage the teeth 8 when upward pressure on the shaft by the tension member 16 is released.

A cylindrical sleeve 45 may be positioned about the shaft 36 and the spring 42 to protect these 45 parts from injury and prevent the accumulation of dust and lint thereon. The parts may be assembled by first placing the spring 42 in the sleeve 45 and inserting the shaft 36 after the sleeve is located properly between the lug 34 and arm 12. Slots 46 formed in the sleeve allow the insertion 50 of the pin 44 and the connection of the end portion of the spring thereto.

A post 48 may be carried by the base 1 and located substantially parallel with the spindle 3 for supporting a spring pressed equalizing member 50 in position to engage the cord material wound upon the bobbin and exert a retarding action thereon effective during the intervals when the detent 37 is raised out of engagement with the teeth 8. One or more tension springs 51 may 55 be coiled about the post 48 for pressing the equalizing member 50 into frictional engagement with the cord material on the spool, which spring may also be shaped to provide a support for the equalizing member 50, if desired, after the manner shown in Fig. 2. The ends of the spring 51 are shown as anchored to the post 48 or base 1, as at 52 and 53, to provide for the application of suitable pressure upon the equalizing member 50.

The parts are shaped to provide adequate clearance between the lower vertical portion of the frame 1 and the tension member 16, as indicated at 54, whereby the tension member is maintained entirely out of contact with the frame member 10 during its vertical movement and is slidably supported solely by the guide members 14 and

15. In this way there is no material frictional resistance to the movement of the tension member, and the cord is maintained substantially out of abrading engagement with the moving parts of the frame and tension member. 5

In the operation of the structure shown, a spool 5 of the type of cord desired for use is placed on the spindle 3 and the cord end passed through the guide opening 26, guide member 29 and delivery eye 30 for incorporation in the material to be formed. In removing or replacing a spool 5, the detent 37 is first turned outwardly 10 against the tension of the spring 42 to permit the removal of the spool, and is returned to its operative tooth engaging position by the spring 15 42 after a fresh spool has been placed on the spindle. The operation of the braider draws cord from the spool 5, which is held against rotation by the detent 37 engaging one of the teeth 8, until the tension member 16 is drawn upwardly against 20 the force of the springs 33 applying tension to the cord. As the applied tension increases, beyond a predetermined point which may be regulated by the strength of the springs 23, the lug 40 engages the shaft 36 to raise the detent 37 25 out of contact with a tooth 8. The shaft 36 and detent 37 are quickly returned to their initial positions by the spring 42 after the tooth is released to bring the detent 37 into engagement with the next or a suitable succeeding tooth of the series. At the same time the tension member falls to a lower tensioning position and the same operation is repeated. In this way the coiled springs 33 tend to maintain a substantially uniform tension varying within a narrow range upon the cord 27 as it passes from the spool 5 through the thread delivery eye for incorporation into the material. 30

In the present construction the tension member 16 is slidably supported entirely by the guide members 14 and 15 and is out of direct contact with the frame member 10, whereby greatly increased freedom of movement of the tension member 16 is obtained and at the same time from the arrangement of the parts the cord 27 is maintained generally out of contact with the surface of the frame to prevent soiling or abrasion of the cord. 40

The guide members 14 and 15, being each firmly supported at opposite ends provide rigid guides 50 for the tension members and insure a high degree of uniformity in its operation. By means of the present construction the guide members 14 and 15 may be readily removed and replaced 55 at any time without dismantling the structure, either for the purpose of replacing the guide members or to substitute springs 23 of different strength if desired.

It will be noted also that the cord guide 29 carried by the tension member is of such construction as to permit easy threading and is also located in spaced relation with the frame 10 so that the cord is maintained substantially out of contact with the frame except, as it passes 65 through the guide opening 26. The provision of a cylindrical cover plate 44 for the shaft 36 and spring 42 serves to insure a more uniform operation of these parts by preventing the accumulation of dust and lint upon the spring 42. 70

The spring pressed equalizing member 50 frictionally engages the cord material on the spool 5 with a force which diminishes as the cord material passes from the spool, thereby tending to equalize the length of cord released at each actu- 75

ation of the shaft 36 and rendering more uniform the feeding of cord from the spool.

What we claim is:

1. In a cord strand carrier for braiding machines, a base portion provided with a bobbin carrying spindle and having a fixed frame carried thereby and located in substantial parallelism with said spindle, spaced guide members fixedly supported by said base portion and frame at opposite ends thereof, a tension member slidably mounted upon said spaced guide members and spaced from said frame, resilient means engageable with portions of said spaced guide members and said tension member for applying tension to a cord, and means carried by said tension member and located outwardly of said fixed frame for receiving a cord from the bobbin to guide the same and apply tension thereto while maintaining the same at all times outwardly of the contiguous surfaces of said fixed frame and tension member.

2. In a cord strand carrier for braiding machines, a base portion provided with means for rotatably supporting a bobbin and having a fixed frame member carried thereby and located in substantial parallelism with the bobbin support, spaced guide members removably supported in said fixed frame member and base portion, a tension member slidably supported by said spaced guide members and having a portion located outwardly of and spaced from said fixed frame member, said fixed frame member being provided with thread guiding means and a thread delivery eye, and means carried by said tension member and located outwardly of said fixed frame member for guiding a cord strand from said fixed frame member to said cord delivery eye while maintaining the same substantially out of direct contact with the outer surface of said fixed frame member.

3. A cord strand carrier for braiding machines comprising a vertically positioned bobbin carrying spindle, vertically positioned guide members each having the opposite ends thereof fixedly supported for guiding opposite sides of a tension

member, a tension member slidably supported by said guide members, spring means between each, said guide member and the tension member exerting balanced tension upon opposite sides of said tension member, a cord delivery member, a stationary cord guide, and a movable cord guide carried by said tension member for applying tension to the cord at a point intermediate the stationary cord guide and cord delivery member.

4. A strand carrier for braiding machines comprising a base provided with a bobbin supporting spindle, a frame member carried by the base located in opposed relation with said spindle, arms extending outwardly from opposite sides of said frame member, detachable guide members each removably supported in fixed relation with the frame by one of said arms and the base respectively, a tension member slidably supported by said guide members and spaced from said frame member, spaced strand guiding means carried by said frame member, and means carried by said tension member for guiding and tensioning the strand engageable with the strand between the spaced strand guiding means and so positioned as to maintain that portion of the strand between the strand guiding means substantially out of contact with the frame member.

5. In a cord carrier for braiding machines, a base provided with a vertically positioned bobbin carrying spindle and having a frame member carried thereby and located in substantial parallelism with the spindle, a bobbin carried by said spindle, vertically positioned fixed guide members supported by said base and frame, a tension member slidably supported by said guide member, cord guiding means carried by said frame and tension member respectively for guiding the cord and subjecting the same to tension from said tension member, and a resiliently actuated equalizing member mounted for frictional engagement with the cord material on the bobbin for equalizing the lengths of cord discharged from the bobbin during corresponding time intervals.

ROGER M. SCOTT.
